DESIGN FOR A BELT BUCKLE

William A. Nelson, Houston, Tex., assignor to
Nelson-Bringolf, Inc., Houston, Tex., a corpora-
tion of Texas

Application November 18, 1946, Serial No. 134,880

Term of patent 3½ years

(Cl. D17—1)

To all whom it may concern:

Be it known that I, William A. Nelson, a citizen of the United States, residing at Houston, Texas, have invented a new, original, and ornamental Design for a Belt Buckle, of which the following is a specification, reference being had to the accompanying drawing, forming part thereof.

Figure 1 is a plan view of a belt buckle showing my new design; and

Figure 2 is a side elevational view of the same.

I claim:

The ornamental design for a belt buckle, as shown.

WM. A. NELSON.
